WATER TUBE BOILER

Heinrich Verkauf, Berlin-Schmargendorf, Germany

Application April 29, 1952, Serial No. 284,875

Claims priority, application Germany May 5, 1951

1 Claim. (Cl. 122—488)

The invention relates to a water tube boiler and more in particular to a water tube boiler with a steam separator and with a group of evaporator tubes connected to an upper and lower collector box in which the lower collector box is connected to the water space of the separator and the upper box communicates with the separator approximately at the height of the mean water level.

The invention aims to provide means for improving the circulation in the evaporator tubes and to relieve the steam separator by pre-separation of boiler water.

The invention contemplates to provide upper collector boxes of two or several groups of tubes and to connect the collector boxes so as to discharge into a common, non-heated return pipe.

This arrangement offers the advantage, that a portion of the liquid working medium taken from the steam-water mixture in the groups of tubes will flow back directly into the lower collector boxes. In the return pipe a lowering of the water level occurs and that level will be the lower the more steam-water mixture enters the return pipe. With the lowering of the water level, the quantity of water separated from the steam-water mixture will increase, and, consequently, the effect of the return pipe will increase correspondingly. Such desirable effect will be obtained by conducting the steam-water mixture from two or more than two groups of tubes into a common return pipe.

It is another object of the invention further to increase the mentioned effect of water separation by so arranging the collector boxes that they open in the common return pipe at a predetermined angle, e. g. a right angle. A discharge into the return pipe in a tangential direction is advantageous as thereby especially much water will be drained.

The invention further aims to improve the pre-separation and direct return of boiler water by-passing the steam separator, by providing communication of the upper portions of the return pipe with the steam space of the separator through a connecting pipe. This causes steam and water to flow in the upper collector boxes in the same direction. Furthermore, the steam flowing towards the return pipe takes the separated water along in the same direction.

Another object of the invention is to design a return pipe or a plurality of return pipes together with the downcomers as parts of the boiler frame.

Furthermore objects and details of the invention will be apparent from the description given hereinafter and the accompanying drawing illustrating an embodiment thereof by way of example. In the drawing:

Fig. 1 is a diagrammatical illustration of the principle of the invention;

Fig. 2 is a longitudinal section of a boiler according to the invention;

Fig. 3 is a cross-section of the embodiment of Fig. 2 in a horizontal plane;

Fig. 4 is a side elevation of the connection of parts of the boiler of Fig. 2, and

2

Fig. 5 is a horizontal cross-section of a modified form of connection of such parts.

Referring now to the drawing, in Fig. 1, the reference numerals 1 and 2 denote two groups of water tubes of which only the axes are indicated by dash and dot lines. These tubes may be arranged on the walls of the fire space and the groups may be located in planes at a right angle to each other. The parallel water or evaporator tubes 1 and 2 rise from the lower collector boxes 3 and 4, respectively, which may be in the form of pipes, and open into the upper collector boxes or pipes 5 and 6, respectively. The lower collector boxes 3 and 4 are connected by the downcomer 7 to the water space of the steam separator or header 8, whereas the upper collector boxes 5, 6 are connected to the steam separator 8 approximately at the height of the mean water level. The steam-water mixture created in the evaporator tubes of the groups 1 and 2 flows into the upper collector boxes 5 and 6, which open into a return pipe 9. The discharge of two jets of a steam-water mixture into the pipe 9 promotes the separation of water by returning it through that pipe. Inasmuch as the steam can flow only towards the separator 8, the major portion of the water following the way of least resistance will flow towards the return pipe 9 and will, thus, be restored into the circulation course on its shortest way, by-passing the separator 8. Thus, the direction of flow of the water in the collector box 6 is the same as that of the steam; in the collector box 5, however, the water has to flow partly in the direction opposite to that of the steam. This is not harmful when the cross-section of the collector boxes is large, that means when the speed of the steam is not too high. If, however, the speed of the steam is high in the upper collector boxes, the draining of the water from the collector box 5 to the return pipe 9 may be hampered by the counter current of the steam. In such a case it is advisable to connect the upper end of the return pipe 9 by means of a connecting pipe 10 to the steam space of the separator 8. Thereby it will be attained that a portion 35 of the steam in the collector box 5 flows also in the direction towards the return pipe with the result that the flow of the water in that direction will be accelerated. This pre-separation relieves the steam separator 8 quite considerably. The entering steam-water mixture will be of a 40 relatively low humidity, that means it will contain only relatively small quantities of water for the separation of which a relatively small steam space will be sufficient, so that the steam separator can be smaller than generally required for equal evaporation. It will be apparent that 45 the invention renders possible also a reduction of the downcomers 7, since large quantities of circulating water flow back directly through the return pipes 9, and only as much boiler water flows to the tube system through the downcomers 7 as corresponds to the quantity of the working 50 medium entering the separator. In consequence, the number and diameter of the bores in the separator for the connection of the downcomers can be reduced so that the wall of the separator will be less weakened and, therefore, the thickness of the wall may be dimensioned smaller. 55 With small or medium steam output, in general, two downcomers 7 will suffice which may simultaneously serve as supports for the separator 8 and may be combined with the return pipes 9 and the upper and lower collector boxes or pipes 3, 4, 5 and 6 to form a water cooled 60 boiler frame. In that case, a separate frame can be dispensed with entirely. The frame of pipe members may support not only the heating surface of the boiler with or without a superheater and feedheater, but also an outer insulation and a sheet metal cover if present. 65 In the embodiment illustrated in Figs. 2 and 3, there is a front group of tubes 11 and two side groups 12 indicated in Fig. 2 by the dash and dot lines of the tube axes. The 70

group 11 extends from the lower tubular collector box 13 to the upper tubular box 14 whereas the tube groups 12 located on the side walls extend from the lower collector boxes 15 to the upper boxes 16. According to the invention, the upper collector boxes are connected to the return pipes 9 which are located in the corners between the groups 11 and 12. The upper end of each pipe 9 communicates through a pipe 10 with the steam space of separator 8 which is supported by the downcomers 7. The downcomers communicate at their top ends with the water space of the separator and through their lower portions with the collector boxes 15. Most of the steam-water mixture created in the tube groups 11 and 12 will be separated in the upper collector boxes. A portion of the separated water flows directly back through pipe 9 into the course of circulation, whereas the created steam flows from the upper collector boxes or through the pipes 10 to the steam separator. In order to protect the return pipes 9 against heating, the adjacent evaporator tubes 17 may be provided with ribs 18.

The connection of two or more than two collector boxes or pipes with one return pipe in a corner point sometimes causes difficulties in the production so that it becomes necessary to arrange one of the pipes off set with respect to the point of intersection. A recommendable connection of the upper collector pipes 14, 16 with the return pipe 9 is shown in Fig. 4, whereby the mentioned drawback can be avoided. For this purpose, the return pipe 9 is provided at its upper end with a wider piece 19 which is jointed by a tapering piece 20 to the pipe 9. This promotes the separation of steam and water, and the connection of the upper collector pipes with the return pipe is simplified as the upper collector pipes open into the piece 19 on approximately the same level. The connecting pipe 10 through which the steam can flow to the separator is also connected to the piece 19 by means of a tapering piece 21. In a similar manner the lower collector pipes may be connected to the return pipes 9.

Fig. 5 illustrates a modified connection of the collector pipes 14 and 16 with the piece 19, wherein the collector pipes discharge into the return pipe in tangential directions, so that the separation of steam and water is promoted by a centrifugal or slinging effect.

Although I have shown only one embodiment of my invention, it will be apparent to those skilled in the art

that many modifications and alteration thereof are possible without departure from the essence and spirit of my invention which for that reason shall not be limited but by the scope of the appended claim.

I claim:

In a water tube boiler the combination of a steam separator drum including a steam space and a water space, a first group of evaporator tubes in a first vertical plane, a second group of evaporator tubes in a second vertical plane forming a corner with said first plane remote from said drum, a lower and an upper horizontal collector box for each of said groups of tubes having their ends connected to the associated collector boxes, a vertical non-heated tube at said corner and constituting a return pipe, said lower collector boxes being connected with one of their ends to the lower portion of said return pipe, the other end of the lower collector box of said first group being connected to the water space of said drum, said upper collector boxes of both said groups being located in one plane substantially at the height of the mean water level in said drum, and being connected with one of their ends to the upper end portion of said return pipe at right angles to the latter, the other end of the upper collector box of said first group being connected to said drum substantially at said height of said mean water level, and a steam conveying pipe connected to said return pipe with one of its end portions in a vertical continuation of said return pipe above the connection of said upper collector boxes and with its other end to the steam space of said drum, so as to cause in each of said upper collector boxes steam to flow in the same direction as water towards said return pipe.
